US0D1105120S

(12) **United States Design Patent** (10) Patent No.: **US D1,105,120 S**
 (45) Date of Patent: ** Dec. 9, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Christian Xavier Dalonzo**, San Francisco, CA (US); **Stephen O. LeMay**, Palo Alto, CA (US); **Grant R. Paul**, San Francisco, CA (US); **Loïc A. Sander**, Sunnyvale, CA (US); **Eric Lance Wilson**, San Jose, CA (US); **Giancarlo Yerkes**, San Francisco, CA (US)

(73) Assignee: **Apple Inc.**, Cupertino, CA (US)

(**) Term: **15 Years**

(21) Appl. No.: **29/946,520**

(22) Filed: **Jun. 9, 2024**

(51) **LOC (15) Cl.** 14-04

(52) **U.S. Cl.**

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
